UNITED STATES PATENT OFFICE.

LAWRENCE RITTELMAN, OF JERSEY CITY, NEW JERSEY, FREDERICK A. WATTE, OF NEW YORK, AND CHARLES H. EBBETS, JR., OF BROOKLYN, NEW YORK, ASSIGNORS TO SALES PRINTING CORPORATION, OF NEW YORK, N. Y., A CORPORATION OF NEW YORK.

TICKET BOOK.

Application filed December 20, 1924. Serial No. 757,128.

This invention relates to ticket books and similar devices, the tickets of which have relative values; and the object of the invention is to provide a device of the class specified employing a multiplicity of ticket members bound together at one end, the tickets being scored adjacent the bound end whereby when the separate tickets are dissected, a binder portion remains and the resulting ticket is oblong and rectangular in form and may be used as an admission ticket to a bazaar or other affair; a further object being to provide on the separate tickets a number preferably positioned thereon adjacent the bound portion; a further object being to provide other visible symbol indicating data on the separate tickets, such for example as names of towns, numbers, etc.; a further object being to provide a wrapper or jacket for the tickets with means for binding and securing the same to the bound portion of the tickets; a further object being to provide means for preventing the compression of the sides of the tickets; a still further object being to provide bound means extending a predetermined distance into and in parallel relation with the tickets, and upon which one of the second named symbol indicating data is applied; and with these and other objects in view, the invention consists in a device of the class and for the purpose specified, which is simple in construction, efficient in use and which is constructed as hereinafter described and claimed.

The invention is fully disclosed in the following specification, of which the accompany drawing forms a part, in which the separate parts of our improvement are indicated by suitable reference characters in each of the views, and in which:—

Fig. 1 is a perspective view of the complete device in sealed position.

Fig. 2 is a perspective view showing parts of the device in extended position.

Fig. 3 is a sectional view on the line 3—3 of Fig. 1 and indicating the position the device assumes when permitting the removal of tickets.

Fig. 4 is a section on the line 4—4 of Fig. 3.

Fig. 5 is a perspective view diagrammatically illustrating the detachment of a ticket.

Fig. 6 is a perspective detail view of the

bound end portion of a device such as 55 shown in Figs. 1 and 2 and illustrating a modification; and,

Fig. 7 is a perspective view of the free edge portion of a device showing another modification.

In the construction shown in Figs. 1 to 5 inclusive, we provide a predetermined number of sheets of paper or cardboard 10 divided by a score line 11 into ticket portions 12 and stub portions 13. The ticket portions 12 are printed in any suitable manner or with any suitable data thereon and may be printed to give an admission value thereto; and preferably in one corner portion of the separate tickets 12 is printed or otherwise arranged symbol indicating numbers as indicated at 14, the numbers being irregularly arranged on the separate tickets as stacked and bound together by a wire stitching 15 passed through the stub portions 13. Printed or otherwise affixed to the free edge portion of the separate tickets are other symbol indicating data 16.

We also provide a casing or jacket 17 within which the tickets 12 and stubs 13 are placed and to which the same are fixedly secured, said casing or jacket comprising a suitably fashioned sheet of cardboard or heavy paper, one end portion of which is folded to form one facing 18 for the tickets 12 and provided with side flaps 19 foldable around the side edges of the tickets 12 and upon the opposite face thereof, and a wire stitching 20 is passed through the facing 18 and through the stub portions 13 of the tickets 12 and through the flaps 19 as clearly seen in Figs. 2 and 4 of the drawing, and this construction securely binds the tickets or the stub portions thereof within the casing or jacket 17 and within the first named end portion thereof. The other end portion

of the casing or jacket comprises an elongated part 21 foldable around the bound edge of the tickets and upon the flaps 19, and at the free end of the part 21 is a flap 22 which passes around the protruding portions of the tickets and extends into the first named end portion of the casing or jacket between the tickets and the wall 18.

When the casing or jacket has been folded into closed position as above set out, a sealing band 23 of strong paper or of fabric is passed around the free edge portions of the

parts 18 and 21, and the edge portions of the flaps 19, and a rupturable seal 24 is pasted or otherwise secured to the flap 22 and the adjacent portion of the sealing band 23 as seen in Fig. 1.

In making up the tickets 12 from the paper or other sheets 10, it is preferred that a slip of paper or like material 25, folded as shown at 26, be placed within the bound portions 13 and bound therewith by the wire stitch 15; and on the folded paper 25 and upon its inner face is arranged data which will be similar to the symbol indicator 16 on one of the tickets 12 within the complete package or book. It is also preferred that when the casing or jacket 17 is composed of comparatively light material, that a stiffening and reinforcing member 27 be mounted within the casing or jacket portion of the tickets to prevent the movement of the side edges of the complete book, together or toward each other in the attempt to read or detect the symbol indicator numbers 14 on the separate tickets 12. In other words, by using the reinforcing member 27, the possibility of seeing or inspecting the numbers 14 is obviated and in the construction shown, the member 27 is mounted between predetermined sheets of the papers 10 and is bound therewith by the wire stitches 15, it being noted that the free edge of the member 27 terminates at the free edge of the casing or jacket 17, and it will also be apparent that the member 27 fits snugly within the side walls of the casing or jacket formed by the side portions of the flap 19. It will be understood however, that we are not necessarily limited to any specific location of the member 27 nor to the material from which it is constructed.

From the foregoing, it will be apparent that when the ticket book is in sealed position as shown in Fig. 1, access to or the removal of the separate tickets 12 can only be accomplished by breaking the rupturable seal 24 which will detect the fact that the package has been opened, and after said seal is broken, any number of the tickets may be removed from the package at will, the same being sold by the symbol indicating data 16. The merchandise ticket is designated by the folded sheet of paper 25 which is removed by destroying the wrapper or casing or jacket 17 when all of the tickets have been sold and removed from the book. It will also be apparent that when the ticket book is in the position shown in Fig. 3 of the drawing, all of the tickets 12 are securely retained in the casing or jacket through the bound portions 13 thereof, and said tickets can only be removed by tearing off at the score line 11, unless the seal 23 is destroyed or the casing or jacket as a whole destroyed.

It is also preferred that two merchandise designating numbers will be printed on the

outside of the casing or jacket, such for example as the numbers 71 and 8, see Fig. 1 of the drawing, and in selecting the separate tickets 12, if a party removes a ticket on which one of the numbers 71-8 appears, such ticket entitles the purchaser to predetermined merchandise.

In Fig. 6 of the drawing, we have shown a slight modification of the construction shown in Figs. 1 to 5 inclusive, which consists in providing a different method or arrangement of the scoring shown in said figures; and in Fig. 6, one sheet 10 is scored as shown at 28, and the next adjacent sheet as shown at 29, whereby one ticket 12 is longer than the other, and also whereby the numerals 14 on the longer tickets will be covered by the bound portion of the shorter tickets.

In Fig. 7 of the drawing, we have shown another modification in which the tongue member 22 is omitted on the casing or jacket and the seal 23 is made a bit wider than in the construction shown in Fig. 1 of the drawing, and the separate sheets 10 or the tickets 12 thereof are cut to form movable portions 12^a on which the data 16 is applied, and the seal 23 is weakened and rupturable adjacent the cut portions of the tickets to permit the parts 12^a to be moved with respect to the remaining or bound portion as clearly illustrated in Fig. 7 and also to facilitate the removal of the separate tickets. With this construction, the free edge portions of the tickets are protected by the casing or jacket 17 and the seal 23 passed therearound as will be apparent.

It will be understood that while we have shown certain details of construction for carrying our invention into effect, that we are not necessarily limited to these details and various changes therein and modifications thereof, may be made within the scope of the appended claims without departing from the spirit of our invention or sacrificing its advantages.

Having fully described our invention, what we claim as new and desire to secure by Letters Patent, is:—

1. A device of the class described comprising a plurality of tickets secured together by a bound portion from which the separate tickets are removable, a wrapper enclosing the bound portion and tickets, means for securing the tickets within and to said wrapper whereby the tickets only are removable therefrom, and means involving a rupturable seal for forming a closure for the entire device.

2. A device of the class described comprising a plurality of tickets secured together by a bound portion from which the separate tickets are removable, a wrapper enclosing the bound portion and tickets, means for securing the tickets within and to said wrap-

per whereby the tickets only are removable therefrom, means involving a rupturable seal for forming a closure for the entire device, and means for reinforcing the wrapper to prevent compression thereof.

3. A device of the class described comprising a plurality of tickets secured together by a bound portion from which the separate tickets are removable, a wrapper 10 enclosing the bound portion and tickets, means for securing the tickets within and to said wrapper whereby the tickets only are removable therefrom, means involving a rupturable seal for forming a closure for the entire device, means for reinforcing the wrapper to prevent compression thereof, and a symbol indicator sheet bound and sealed within the entire device.

4. A device of the class described comprising a plurality of sheets of predetermined material on which predetermined data is fixed, said sheets being secured together through a bound portion from which the separate sheets are detachable, and predetermined symbol indicator data on each of said sheets, one of said symbol indicator data constituting a plurality of numerals arranged on said sheets adjacent the bound portion thereof, and being irregularly arranged on said bound sheets.

5. A device of the class described comprising a plurality of sheets of predetermined material on which predetermined data is fixed, said sheets being secured together through a bound portion from which the separate sheets are detachable and predetermined symbol indicator data on each of said sheets, one of said symbol indicator data constituting a plurality of numerals arranged on said sheets adjacent the bound portion thereof and being irregularly arranged on said bound sheets, and another sheet of less dimensions than the first named sheets and secured to the bound portion and having thereon sealed symbol indicator data.

6. A device of the class described comprising a plurality of sheets of predetermined material on which predetermined data is fixed, said sheets being secured together through a bound portion from which the separate sheets are detachable and predetermined symbol indicator data on each of said sheets, one of said symbol indicator data constituting a plurality of numerals arranged on said sheets adjacent the bound portion thereof and being irregularly arranged on said bound sheets, another sheet of less dimensions than the first named sheets and secured to the bound portion and having thereon sealed symbol indicator data, and means involving a casing or jacket for irremovably binding and sealing said sheets therein.

7. A device of the class described comprising a plurality of sheets of predeter-

mined material on which predetermined data is fixed, said sheets being secured together through a bound portion from which the separate sheets are detachable and predetermined symbol indicator data on each of said sheets, one of said symbol indicator data constituting a plurality of numerals arranged on said sheets adjacent the bound portion thereof and being irregularly arranged on said bound sheets, another sheet of less dimensions than the first named sheets and secured to the bound portion and having thereon sealed symbol indicator data, means involving a casing or jacket for irremovably binding and sealing said sheets therein, and means for reinforcing said casing or jacket.

8. A device of the class described comprising a plurality of sheets of predetermined material on which predetermined data is fixed, said sheets being secured together through a bound portion from which the separate sheets are detachable and predetermined symbol indicator data on each of said sheets, one of said symbol indicator data constituting a plurality of numerals arranged on said sheets adjacent the bound portion thereof and being irregularly arranged on said bound sheets, another sheet of less dimensions than the first named sheets and secured to the bound portion and having thereon sealed symbol indicator data, means involving a casing or jacket for irremovably binding and sealing said sheets therein, and means for reinforcing said casing or jacket, said means being bound within and to the casing or jacket and the bound portion of said sheets.

9. A device of the class described comprising a plurality of sheets of predetermined material on which predetermined data is fixed, said sheets being secured together through a bound portion from which the separate sheets are detachable, predetermined symbol indicator data on each of said sheets, and another sheet of less dimensions than the first named sheet and secured to said bound portion and having thereon sealed symbol indicator data.

10. A device of the class described comprising a plurality of tickets secured together by a bound portion from which the separate tickets are removable, a casing entirely enclosing the major portion of said tickets and to which the tickets are secured through the bound portion thereof, and means for sealing the projecting end portions of the tickets which means must be ruptured in the removal of said tickets.

11. A device of the class described comprising a plurality of tickets secured together by a bound portion, a casing enclosing the major portion of said tickets and the bound portion thereof, means for sealing the bound portion of the tickets to said casing,

and means on said casing forming a seal and enclosure for said first named sealing means.

12. A device of the class described comprising a plurality of tickets secured together by a bound portion, a casing enclosing the major portion of said tickets and the bound portion thereof, means for sealing the bound portion of the tickets to said casing, means on said casing forming a seal and enclosure for said first named sealing means, and said casing being provided with a projecting flap adapted to be passed around the projecting end portions of said tickets and to be normally sealed to the container to prevent the removal of said tickets.

13. A device of the class described comprising a plurality of tickets secured together by a bound portion, a casing enclosing the major portion of said tickets and the bound portion thereof, means for sealing the bound portion of the tickets to said casing, means on said casing forming a seal and enclosure for said first named sealing means, and said tickets being provided with predetermined data thereon adjacent said bound portion.

14. A device of the class described comprising a plurality of tickets secured together by a bound portion, a casing enclosing the major portion of said tickets and the bound portion thereof, means for sealing the bound portion of the tickets to said casing, means on said casing forming a seal and enclosure for said first named sealing means, said tickets being provided with predetermined data thereon adjacent said bound portion, and means fixedly mounted in the casing for preventing the collapsing of the casing and said tickets whereby the detection of the data on said tickets adjacent the bound portion is prevented.

15. A device of the class described comprising a plurality of tickets secured together by a bound portion, a casing enclosing the major portion of said tickets and the bound portion thereof, means for sealing the bound portion of the tickets to said casing, means on said casing forming a seal and enclosure for said first named sealing means, said tickets being provided with predetermined data thereon adjacent said bound portion, means fixedly mounted in the casing for preventing the collapsing of the casing and said tickets whereby the detection of the data on said tickets adjacent the bound portion is prevented, and that part of the tickets projecting beyond said casing being provided with predetermined data thereon.

16. A device of the class described comprising a plurality of tickets secured together by a bound portion, said tickets being of different lengths and alternately arranged whereby the bound portion of a short ticket will overlie a predetermined portion of an adjacent longer ticket.

17. A device of the class described comprising a plurality of tickets secured together by a bound portion, said tickets being of different lengths and alternately arranged whereby the bound portion of a short ticket will overlie a predetermined portion of an adjacent longer ticket, and a container for the major portion of said tickets and the bound portion thereof.

18. A device of the class described comprising a plurality of tickets secured together by a bound portion, said tickets being of different lengths and alternately arranged whereby the bound portion of a short ticket will overlie a predetermined portion of an adjacent longer ticket, a container for the major portion of said tickets and the bound portion thereof, and means for sealing said bound portion within and to said container.

19. A device of the class described comprising a plurality of sheets having indicator data thereon, said sheets being secured together through a bound portion from which the separate sheets are adapted to be severed along a straight line traversing said sheets to form of the severed sheets tickets of rectangular form, and means enclosing a predetermined portion of said sheets and bound portions thereof for sealing the indicator data within said means.

20. A device of the class described comprising a plurality of sheets having indicator data thereon, said sheets being secured together through a bound portion from which the separate sheets are adapted to be severed along a straight line traversing said sheets to form of the severed sheets tickets of rectangular form, means enclosing a predetermined portion of said sheets and bound portions thereof for sealing the indicator data within said means, and means for fixedly retaining the bound portions of said sheets to said last named means.

21. A device of the class described comprising a plurality of sheets having indicator data thereon, said sheets being secured together through a bound portion from which the separate sheets are adapted to be severed along a straight line traversing said sheets to form of the severed sheets tickets of rectangular form, means enclosing a predetermined portion of said sheets and bound portions thereof for sealing the indicator data within said means, means for fixedly retaining the bound portions of said sheets to said last named means, and the projecting portions of said sheets having predetermined data thereon.

22. A device of the class described comprising a plurality of sheets having indicator data thereon, said sheets being secured together through a bound portion from which the separate sheets are adapted to be severed along a straight line travers-

ing said sheets to form of the severed sheets
tickets of rectangular form, means enclosing
a predetermined portion of said sheets and
bound portions thereof for sealing the indi-
5 cator data within said means, means for fix-
edly retaining the bound portions of said
sheets to said last named means, the project-
ing portions of said sheets having pre-
determined data thereon, and sealing means
10 secured to the bound portions of said sheets
and having thereon indicator data.

23. A device of the class described com-
prising a plurality of sheets having indica-
tor data thereon, said sheets being secured
15 together through a bound portion from
which the separate sheets are adapted to be
severed along a straight line traversing
said sheets to form of the severed sheets

tickets of rectangular form, means enclosing
a predetermined portion of said sheets and
bound portions thereof for sealing the in-
dicator data within said means, means for
fixedly retaining the bound portions of said
sheets to said last named means, the project-
ing portions of said sheets having predeter-
mined data thereon, sealing means secured
20 to the bound portions of said sheets and
having thereon indicator data, and means
for preventing lateral collapsing of the
sheets when bound and sealed.

25 In testimony that we claim the foregoing
as our invention we have signed our names
this 17th day of December, 1924.

LAWRENCE RITTELMAN.
